UNITED STATES PATENT OFFICE.

BENNET D. HAEUSSLER, OF MARION, IOWA.

DESIGN FOR A WAITING-STATION BOOTH.

Application filed November 10, 1925. Serial No. 15,399. Term of patent 14 years.

To all whom it may concern:

Be it known that I, BENNET D. HAEUSSLER, a citizen of the United States of America, residing at Marion, in the county of Linn and State of Iowa, have invented a new, original, and ornamental Design for a Waiting-Station Booth, of which the following is a specification, reference being had to the accompanying drawing, forming a part hereof.

In the drawing:

Figure 1 is a perspective view, and
Fig. 2 is a plan view.

I claim:

The ornamental design for a waiting station booth, as shown.

BENNET D. HAEUSSLER. [L.S.]
